[57] **CLAIM**

The ornamental design of a document storage and display unit, as shown and described.

DESCRIPTION

FIG. 1 is a front perspective view of a first embodiment of the document storage and display unit embodying our design;

FIG. 2 is a front view thereof;

FIG. 3 is a rear view thereof;

FIG. 4 is a top plan view thereof;

FIG. 5 is a right side view thereof, the left side view being a mirror image thereof; and,

FIG. 6 is a perspective view of a second embodiment of the document storage and display unit which is identical to the first embodiment except that the rear portions of the shelves are defined by mesh-like screens including openings which penetrate through the screens.

1 Claim, 5 Drawing Sheets
